UNITED STATES PATENT OFFICE.

GEORGE S. HIRAKAWA, OF SUISUN, CALIFORNIA.

MACHINE FOR PACKING ASPARAGUS.

Application filed September 26, 1927. Serial No. 222,027.

This invention relates to a machine for assembling asparagus shoots and packing them into the boxes for shipment together with the method of so arranging the asparagus shoots as to expedite the packing of the shoots for shipments in crates which will prevent them from being bruised.

An object of the invention is to provide a portable stand for assembling the asparagus shoots which may be conveniently moved from place to place as may be required.

A further object of the invention is to provide a removable box or receptacle within which the asparagus shoots may be assembled and which is used to transfer the assembled shoots to the crate.

Another object of the invention is to provide a method of assembling the shoots which will make them more convenient to assemble for transference to the crate and which will insure the proper placing of the shoots in the crates.

Another object of the invention is to provide means for squeezing the shoots together to make a tight package and also to enable the butts to be readily cut off when a crate full of shoots has been prepared.

A further object of the invention is to provide a removable support for the shoots which will enable the receptacle within which the packing is first done to be turned up to transfer the asparagus to the crate when one crate full has been placed in the packing receptacle.

Other objects of the invention will be apparent as the description proceeds.

An embodiment of the invention is shown in the accompanying drawings in which the same reference numeral is applied to the same portion throughout the several figures of the drawings and of which there may be modifications.

Figure 1 is a front elevation of the packing receptacle support,

Figure 2 is a side elevation of the packing receptacle support showing the plate for carrying the cut butts ready to be inserted in position,

Figure 3 is a perspective view of the original packing receptacle,

Figure 4 is a perspective view of the butt support used for transferring the shoots from the packing receptacle to the crate,

Figure 5 is a sectional view of the packing receptacle filled ready to be transferred to the crate,

Figure 6 is a front view of one of the crates showing the padding used on the bottom of the crate, and

Figure 7 is a cross sectional view of one of the crates.

The packing receptacle consists of a rectangular sheet metal box with a bottom 1, ends 2 and 3 and a back 4. This sheet metal box is placed on a supporting shelf 5, which shelf is carried by two cleats 6 and 7 which are secured at right angles to two posts 8 and 9. The posts 8 and 9 are about four feet long and each has a spike as indicated at 10 and 11. Two other cleats 12 and 13 are secured to the two posts 8 and 9 to hold them rigidly in the position shown in Figures 2 and 3. The shelf is at a convenient height for the workman to either stand or sit and place the asparagus tips in the receptacle with the butts outwardly.

In ordinary practice the butts will extend outwardly somewhat beyond the ends 2 and 3 of the receptacle in which they are packed, since as brought in from the field the asparagus shoots will all be of different lengths.

The two posts, when in position for operation are held against the side of a building or bench by means of a screw eye 15 placed in each one with springs 16 and 17 to connect each post to two screw eyes 18 placed in the bench or building against which the packing stand is leaned. A cleat 19 at the back and on the top of the shelf 5 serves to hold the packing receptacle in a fixed position when in use.

Ordinarily the asparagus shoots are packed in the receptacle somewhat higher than its top whereupon the flat lever 21 is brought down upon the top of the asparagus shoots to press them tightly into the receptacle. This lever is locked in the position shown by means of the pivoted latch lever 22, said lever being pivotally connected to the post 9 by means of a lag bolt or other suitable bolt 23. The other end of the lever is connected by means of a pivot pin 24 to a slidable spring bolt 25. The bolt 25 slides in two forwardly projecting ears of a plate 26 which is secured to the post 8 and the lever 21 has a flattened face at 27 to insure holding it upright when not in use, the pressure of the spring acting to hold the flattened face down against the upper ear 110 of plate 26 holds the lever 21 in a vertical position.

When the asparagus has been packed tightly into the receptacle all of the butts of the asparagus shoots will project beyond the back of said receptacle whereupon a long 5 knife is operated by hand to cut off the projecting asparagus butts so that the asparagus shoots will all be substantially of the same length, the bud ends or tips being packed against the sides 4 during the time the receptacle 10 is being filled. As soon as the receptacle has been filled and the butts cut off the plate 30 is placed against the fore part of the asparagus butts, the section 31 being placed under the asparagus shoots said plate 15 30 being then at right angles to the cut off butts. The receptacle with the plate 30 is then lifted bodily and placed so that the tips of the asparagus will occupy the position shown in Figure 5 whereupon the asparagus 20 is transferred to the incomplete crate shown in Figure 6.

The crate ordinarily consists of a bottom 35, two trapezoidal ends 36 and 37, sides 38, 39 secured to each of the sides of the trapezoidal ends, and a top 40, the latter being put on after the asparagus has been placed in the crate. The bottom is padded with some moss as indicated at 41 and two plates with their ends upturned as indicated at 42 25 and 43 are used to hold the moss in place while the asparagus is being put in the crate.

The method of operation is as follows: Assuming the receptacle into which the asparagus shoots are to be placed is first placed on the support, the workman then takes asparagus shoots of different lengths and assembles them in this receptacle with the bud ends or tips against the back wall 4. 30 As soon as the receptacle has been filled to about 20% greater than its ordinary capacity the lever 21 is used to squeeze the asparagus tightly into the receptacle whereupon a long knife is used to cut off the 45 uneven butts even with the outer edges of the ends 2 and 3 of said receptacle. Thereupon the plate 30 is placed in the position shown in Figure 5, the box is then turned up and the entire body of asparagus is placed on the top of the two slides 42 and 43 which 50 crate is ordinarily tilted slightly when the asparagus is being placed therein, and the metal plates at the bottom and the metal of

the packing receptacle are then carefully removed from the asparagus and crate after 55 which the top of the crate is put on and the sides of the crate are placed in position and nailed tight, squeezing the tip ends to the position shown in Figure 7.

The arrangements of the crates is such 60 with respect to the height of the receptacle used for accomplishing the packing that the asparagus tips do not become bruised by touching the inside of the top 40. This arrangement being maintained by reason of 65 the fact that the asparagus tips are always somewhat thicker at the butt than they are at the extreme top so that the ultimate package is slightly wider at the bottom than it is at the top as illustrated in Figure 7. 70

Having thus described my invention, what I desire to secure by Letters Patent of the United States is as follows, but modifications may be made in carrying out the invention as shown in the drawing and in the above 75 particularly described form thereof, within the purview of the annexed claims:

1. An asparagus packing stand comprising a shelf, means to support the shelf at an incline, means to detachably secure the support to the wall of a building, a removable packing receptacle, a cleat on the support to hold said packing receptacle in a given position, a presser arm and a universal hinge on one of the supports for holding said arm to permit it to press the asparagus into place in the packing receptacle or to permit the arms to swing horizontally out of the way of the packer. 85

2. An asparagus packing stand comprising a shelf, portable means to support the shelf in an inclined position, means to detachably secure the support to the wall of a building in the desired position, a cleat on the support to hold a packing receptacle at 90 a given position, a presser arm carried by one of the supports for pressing the asparagus into place in the packing receptacle, and a slideable spring bolt holding one end of said arm to enable it to be turned and held 95 in a position out of the way of the packer. 100

In testimony whereof I have hereunto set my hand this 19th day of September, A. D. 1927.

GEORGE S. HIRAKAWA.
